UNITED STATES PATENT OFFICE.

ANTON C. EGGERS, OF NEW YORK, N. Y., ASSIGNOR TO GOODYEAR'S INDIA RUBBER GLOVE MFG. CO., OF NEW YORK, N. Y., A CORPORATION OF CONNECTICUT.

NEBULIZER.

No. 824,471.

Specification of Letters Patent.

Patented June 26, 1906.

Application filed July 11, 1905. Serial No. 269,205.

To all whom it may concern:

Be it known that I, ANTON C. EGGERS, a citizen of the United States, residing in New York, in the borough of Brooklyn and State 5 of New York, have invented certain new and useful Improvements in Nebulizers, of which the following is a specification.

This invention relates to nebulizers; and has as its primary object to provide improved 10 means for mounting and adjusting the suction-tube embodied in such devices.

To this end the invention consists in a nebulizer embodying the novel features and combinations of parts which will appear herein- 15 after and finally be recited in the claims.

In the accompanying drawings, in which like parts are designated by the same reference characters throughout, Figure 1 is a side elevation of a nebulizer constructed in ac- 20 cordance with the invention; and Fig. 2 is a vertical central section of the same.

Referring to the drawings, 1 denotes the liquid receptacle or container, which may be of any preferred form and is preferably made 25 of glass, as shown, being provided at its mouth with exterior screw-threads.

2 denotes the cap of the improved nebulizer, which is provided with a cylindrical bore 3, having at its lower extremity a number of 30 screw-threads which engage the threads on the mouth of the receptacle, as shown in Fig.

Said cap is provided at one side, slightly above the mouth of the liquid-receptacle, with a lateral screw-threaded opening, into which is screwed a laterally-extending air-tube the bore of which is closed at its inner end, while the outer end of said tube is connected in any suitable way with the air pump or bulb 5, which can be of any preferred form. The 35 lower side wall of the air-tube 4 is provided with a vertically-extending screw-threaded opening, into which is screwed a second air-tube 6, which extends downwardly from said first air-tube at substantially right angles 40 thereto and is provided at its lower or inner end with a hook-shaped extension embodying a laterally-extending web or arm 7, made integral with said air-tube. Said web or arm is provided at a point offset from vertical alinement with the bore 8 of said air-tube, which bore extends downwardly only to the upper portion of the extension and is there provided with a lateral opening 9, with

a vertically-disposed screw-threaded opening, 55 in which is mounted a suction-tube 10, which is provided at its upper portion with exterior screw-threads engaging those of said threaded opening in such a manner as to be vertically adjustable. The upper end of the suction-tube 10 is preferably pointed, as shown, and may 60 be adjusted in a vertical direction relative to the lateral opening 9 in the air-tube 6, which opening is disposed at the same side of said air-tube as said suction-tube.

It is obvious that the form of nozzle or discharge-tube which is used in connection with the improved construction just described is perfectly immaterial; but I have devised a nozzle of particular convenience and utility for use in connection with a nebulizer of the 70 type described. This nozzle (designated in the drawings by the reference character 11) is preferably made integral with the cap 3 and extended upwardly therefrom, being in communication with the upwardly-extending intermediate portion of the passage or bore 13 of the nozzle 11, which latter bore, like said nozzle, has the form of an inverted horseshoe, as shown, so that the discharge ends of said nozzle converge. The discharge ends are of 80 such size and spaced at such a distance as to fit snugly into the nostrils of the person using the nebulizer.

The operation of the improved nebulizer is substantially the same as in other nebulizers 85 now in use. The air being forced from the bulb 5 upwardly through the laterally-extending air-tube 4 and downwardly from said air-tube into the vertical air-tube 6 passes through the lateral opening 9 in said air-tube, 90 whereby an air-blast across the upper end of the suction-tube 10 is created. This air-blast causes a vacuum in the suction-tube 10, whereupon the liquid contained in the receptacle mounts rapidly in said suction-tube 95 until it is struck by said air-blast and forced thereby into a very fine spray, which fills the upper portion of the receptacle 1 and is forced by the air-pressure generated in the bulb upwardly around the air-tube 4, through the 100 bores 3 and 12, and into the nozzle 11, which separates the same into two parts which issue from the discharge ends of said nozzle in converging sprays.

The improved nebulizer has the advantage 105 that the air-tubes and suction-tube are

mounted in such a manner as to be readily removable when desired. The suction-tube is so mounted that the quality of the spray may be easily regulated by screwing this tube either in upward or downward direction through the arm or web 7, so as to vary the action of the air forced through the air-tubes.

Having thus described my invention, I claim as new and desire to secure by Letters 10 Patent—

1. In a nebulizer, the combination, with a liquid-receptacle, of an air-tube extending downwardly through the mouth of said receptacle and provided at its lower end with a laterally-extending arm, said air-tube being provided with a lateral discharge-opening above said arm, and a suction-tube carried by said arm and adjustable vertically with respect to said discharge-opening.

20 2. In a nebulizer, the combination of a liq-

uid-receptacle, an air-tube extending downwardly through the mouth thereof and provided with a laterally-extending arm or web having a vertical threaded opening offset from alinement with the bore of said air-tube, 25 the latter being provided above said arm with a lateral discharge-opening, and a vertically-disposed suction-tube provided with exterior screw-threads engaging those of said threaded opening, said suction-tube extending above said arm and into coöperative relation with said discharge-opening.

In testimony that I claim the foregoing as my invention I have signed my name in presence of two subscribing witnesses.

ANTON C. EGgers.
